UTILITY RACK

Carl S. Hedquist, George A. Johnson, and Eric A. Malmberg, Minneapolis, Minn.

Application October 18, 1937, Serial No. 169,572

2 Claims. (Cl. 211—71)

Our invention relates to utility racks which may also be aptly designated as portable holders arranged to be suspended or fastened on a wall, the panel of a pantry door or any other convenient place within easy reach as in a kitchen.

5 The main object of our invention is to provide a simply constructed, light weight, highly efficient and inexpensive holder for containers of spices, condiments, extracts and other ingredients such as used daily by housewives, a particular feature of this device being its light weight and telescopic construction such that it may be set to certain length to hold a predetermined number of containers, all as hereinafter fully set forth and illustrated in the accompanying drawing, in which:—

Fig. 1 is a front perspective view of our improved utility rack.

Fig. 2 is a direct front view of the device holding five containers of uniform size and one of which is shown partly withdrawn from its seated position.

Fig. 3 is an enlarged scale sectional elevation as on line 3—3 in Fig. 2, looking toward one end 20 of the device, and Fig. 4 is a top view of the right hand end of the utility rack.

Referring to the drawing by reference numerals, like parts being designated by corresponding characters in the several figures; our device 30 comprises preferably two horizontally registering, upright, sheet metal end walls 5 of channel shape in cross section, each having a horizontal bottom edge 5A, a front flange 5B shorter than the rear flange 5C and the upper edge of each end wall 35 cut in an angular line as 5D from the top of the front flange to the top of the rear flange.

The end walls are rigidly but adjustably connected in variously spaced relation to each other by a number of telescopically constructed rails, 40 shown four in number and designated 6, 7, 8 and 9, of which 6 is an upper rear rail connecting the upper rear end parts of the end walls. 7 is a lower rear rail, inward of the rear edge of the device, 8 is a lower front rail connecting the 45 front lower corners of the end walls and 9 is an upper front rail but in a plane lower than the rear upper rail 6.

Each rail is preferably made of two sheet metal telescopic sections, one section of channel shape 50 in cross section and the other rail section a sheet metal flat rail doubled at its edges longitudinally, for strength, and of a size to be guided slidably in the corresponding channel section of the rail. The smaller rail sections may all extend rigidly 55 from one end wall and parallel to each other,

said sections designated 6A, 7A, 8A and 9A to engage slidably in the corresponding channels 6, 7, 8 and 9 extending rigidly from the other end wall, as best shown in Fig. 1.

In each of the rear flanges 5C, near their upper ends is provided a suitable aperture 12, for screws (not shown) to hang or fasten the device on any vertical surface such as a wall or door panel, designated 10 in Fig. 2.

All the rails are of course parallel to each other, 10 and each is flat vertically, the rear lower rail 7—7A comprising a support rail and made narrower than the lower front rail 8—8A so that its top edge is in lower plane than the top edge of said rail 8—8A. On said support rail may be 15 placed any predetermined number of containers 11, in a row, such containers being slipped downwardly between the upper rails, and all resting on the top edge of the rail 7—7A as indicated by dotted lines in Fig. 3.

20 The containers will of course be automatically aligned in the rack, in a neat appearing row, as shown in Fig. 2, the content designations of the containers disclosed in clear view, as in the space between the upper and lower front rails. The 25 front lower rail having its top edge at an elevation higher than the top edge of the support rail 7—7A, the former serves as a guard and aligns the front lower parts of the containers. If the device is set to snugly hold five containers, as shown, 30 or any other number, any one of the containers may be easily removed by pushing its bottom end upwardly, or by contacting the front part of it over rail 9—9A and bearing upwardly.

Our utility rack, as above described, provides 35 a useful holder for uniformly sized containers and is easily set by telescoping it to desired size for a predetermined number of containers.

It is obvious that the rails need not necessarily 40 be of sheet metal. They may comprise two parallel wires and their respective free ends each formed with a loop slidably engaging the other wire. Other modifications may be made without departing from the scope and spirit of our invention.

45 We claim:

1. A utility rack of the class described comprising a pair of upright, horizontally spaced end walls, a number of telescopic parallel rails connecting said end walls in adjustable relation to 50 each other to provide a rack of predetermined length, said telescopic rails located two at the front in vertically spaced and fixed parallel relation, one at the rear and upper part of the rack, and a lower inside rail parallel to the lower 55

front rail but spaced forward from the rear side of the rack, the latter rail comprising support means for containers inserted downwardly in the rack, said lower front rail fixed in a parallel position relative to the support rail but its upper edge in higher plane than the top edge of the support rail, for the purpose set forth.

2. A utility rack of the class described comprising a pair of upright, horizontally spaced end walls, a number of telescopic parallel rails connecting said end walls in adjustable relation to each other, to provide a rack of predetermined length, said telescopic rails located two at the front in vertically spaced parallel relation, one at the rear and upper part of the rack, and a lower

inside rail parallel to the lower front rail but spaced forward from the rear edge of the rack, the latter rail comprising support means for containers inserted downwardly in the rack, said end walls comprising two identical vertically disposed channels, said front rails of the device connecting the front flanges of said channels, the rear upper rail connecting corresponding parts of the rear flanges and the support rail connecting the lower end parts of the webs of the channels as shown and described. 5 10
